UNITED STATES PATENT OFFICE.

BENJAMIN B. VAN DER VEER, OF NEW YORK, N. Y.

DESIGN FOR A SHEET OF WRAPPING-PAPER.

SPECIFICATION forming part of Design No. 22,184, dated January 31, 1893.

Application filed December 8, 1892. Serial No. 454,534. Term of patent 7 years.

To all whom it may concern:

Be it known that I, BENJAMIN B. VAN DER VEER, a citizen of the United States, residing at New York, in the county of New York and State of New York, have invented and produced a new and original Design for a Sheet of Wrapping-Paper, of which the following is a specification, reference being had to the accompanying drawing, illustrating the same.

The drawing shows a face or plan view of my said sheet of wrapping paper.

My design consists of an oblong sheet of wrapping paper, provided with a surface ornamented with a central body having arms radiating therefrom, one of said arms being provided with arms extending at right angles thereto.

1 is the central body, ovoid in shape, substantially as shown.

2, 2, 3, 3, are arms, radiating from the central body 1, and extending to the edges of material 5 of the wrapper.

4, 4, are cross arms, extending at right angles to one of the arms 3.

I claim:—

The design for a sheet of wrapping paper, substantially as shown and described.

BENJAMIN B. VAN DER VEER.
